UNITED STATES PATENT OFFICE

JOHN F. O'ROURKE, OF NEW YORK, N. Y.

DIVING APPARATUS

Application filed March 24, 1928. Serial No. 264,522.

The object of my invention is to provide a portable working chamber by means of which workmen or divers may have access to submerged objects or vessels or to ground underlying water and for various other purposes where the workmen must be protected against water by means of compressed air. In my application Serial No. 105,676, filed April 30, 1926, I showed and described a diving apparatus for the same general purposes and the present case covers features which may be utilized in conjunction with the features disclosed in said copending application.

One object of the present invention is to provide diving apparatus, preferably in the form of a cylinder which may be attached to, or rest upon a sunken vessel or other submerged object, and in conjunction with the diving cylinder I provide means whereby the cylinder may be maintained in a vertical or substantially vertical position while the lower part of the apparatus is attached to the deck of the vessel or other object which is inclined to the vertical. In other words, where the diving apparatus is attached to the deck or hull of a vessel which is in an inclined position, the diving cylinder may be maintained in a vertical or approximately vertical position notwithstanding the difference in the angle between the deck or hull of the submerged vessel and the bottom line of the rigid portion of the diving cylinder. For this purpose I have shown a bottom structure on the lower end of the cylinder which is of a collapsible nature and which may be adjusted in accordance with the difference in the angle of the deck or other member to which the device is to be attached and the angle of the fixed bottom of the diving cylinder. In addition, I provide means for adjusting this collapsible or accordion member from within the diving cylinder to conform to the curvature of the surface to which it is attached in a watertight manner.

Another object of my invention is to provide a telescoping tube which may be folded to at least some extent within the diving cylinder, and this tube is made of sections which may be drawn out or extended, so that when the diving cylinder is attached to a submerged

vessel the tube may be drawn out or extended so that when the diving cylinder is attached to a submerged vessel so that its upper end extends above the water level and forms a means of communication whereby members of the crew of the submerged vessel may pass from the vessel into the diving cylinder and be thence transported through the tube to the surface. It is possible with this apparatus to rescue the crew of the submerged vessel quickly and without subjecting them during the rescue operation to air pressure, so that no decompression operation is necessary when they are discharged at the surface. In addition, any material or objects which are to be salvaged are also carried upwardly through the tube and in fact the tube forms a means of communication between the surface and the diving cylinder while various operations are being carried on. Once the device is in operative position, those working within it may operate in atmospheric pressure and even leave and return to the device without being subjected to pressures higher than in some cases the pressure prevailing in the hull of the sunken vessel.

Another and important advantage of the present device is the provision of means for guying the telescoping tube when in its extended position in order to hold it properly in place against the action of the water currents, wind and waves and in order to relieve excessive strain from the tube itself and from the diving cylinder. The means for guying the tube are simple and effective and may be quickly put into operation. The means are also portable and may remain part of the equipment of the apparatus.

Another object of the invention is to provide simple and effective means for plumbing the rescue or telescopic tube in relation to the diving cylinder so that if the latter is not exactly in a vertical position the telescopic tube need not be inclined but may, nevertheless be maintained in a vertical position. Other features and advantages will be set forth more in detail in the following description of my invention.

In the drawings forming part of this application,

Figure 1 is an elevation of a diving apparatus embodying my invention and showing the same attached to a vessel for rescue purposes,

5 Figure 2 is an elevation of the apparatus with the rescue tube in collapsed position, the shell being partly broken away to show the interior parts,

10 Figure 3 is a vertical sectional view taken on the line 3—3 of Figure 4 with some of the devices within the cylinder omitted for simplicity of illustration,

Figure 4 is a plan view of the device with the telescopic tube in collapsed position,

15 Figure 5 is an enlarged, detail sectional view illustrating parts of the telescopic tube in collapsed position,

Figure 6 is a similar view showing some parts of the tube in extended position,

20 Figure 7 is a view similar to Figure 3 but with the telescopic tube extended and showing the method of plumbing the same,

Figure 8 is a horizontal sectional view taken on the line 8—8 of Figure 7,

Figure 10 is an enlarged, sectional view of the upper portion of the cylinder with the 30 telescopic tube raised to its highest position,

Figure 11 is a similar view showing the relation of the parts when the cylinder is inclined and with the telescopic tube vertically arranged,

35 Figure 12 is an enlarged detail sectional view,

Figure 13 is a sectional view taken on the line 13—13 of Figure 14,

40 Figure 14 is a sectional view showing the parts at the lower end of the cylinder,

Figure 15 is a sectional view taken on the line 15—15 of Figure 14, and

45 Figure 16 is an inverted plan view looking at the bottom of the diving cylinder.

The present apparatus may not only be used for rescuing members of the crew or passengers of a submerged vessel through the hatchway of the latter, but in addition where the vessel is lying on its side, or even 50 capsized, it is possible with the present apparatus to have access to the deck or any portion of the hull which is in the uppermost position, even though it is not exactly horizontal, and to permit the crew to drill, cut or burn an opening through the deck or hull of the submerged vessel for rescue purposes. Thus, if the crew or passengers of the 55 submerged vessel are confined in a water-tight compartment of the submerged vessel which is not provided with a hatchway, nevertheless by using the present apparatus a rescue opening may be made in the submerged vessel for the purpose of rescuing the crew or passengers or for salvaging the contents of the vessel. Although the present apparatus

may be operated in conjunction with a surface vessel, nevertheless when it is installed in operative condition it is not dependent upon the surface vessel, at least until the device is to be taken out of use, so that after 70 it has been installed, the surface vessel may leave the location and return. If after operations have started the sea becomes too rough for the surface vessel to remain in proximity to the present apparatus, the salvaging operations may be continued or suspended until the return of the surface vessel.

75 The diving apparatus consists essentially of a shell 1 preferably but not necessarily of cylindrical form, and having an arched top 2 permanently secured thereto by a watertight joint. I have shown this cylinder divided to form upper and lower compartments 3, 4 by means of a horizontal dividing wall 5 which is shown provided with a downwardly opening door or hatch 6 centrally located and in line with the rescue tube to be hereinafter described. In addition, I have shown a downwardly opening door or hatch 7 by means of which the crew may pass from one chamber to the other when the telescopic tube is down. When these several hatches are closed there is no communication of air pressures between the upper and lower chambers 3, 4 and the upper chamber may remain 80 completely closed against both compressed air and water.

85 The bottom end of the cylinder is provided with an angle metal ring 8 attached to its inner side and the space within this ring is open, so that water would enter the lower compartment 4 except for the presence of compressed air. Within the upper compartment I preferably provide valves 9 for controlling the supply of compressed air which is fed to the diving cylinder through a tube 10 having water tight connection with the top 2 and it leads from a suitable compressed air supply on the surface vessel (not shown) or a cylinder of compressed air (not shown) 90 may be carried when other sources are not available. The valve 9 may be used to release compressed air either within the upper chamber 3 or the valve 11 may be opened to supply, through a connecting tube 12, compressed air to the lower compartment 4, and the compressed air entering the compartment 4 may be so regulated as to equal the external water pressure, so that this air within the lower compartment 4 will prevent the water 95 from entering the open bottom of the diving cylinder. I have also shown a telephone 13 in the upper compartment, connected by suitable wires enclosed in the cable 14 and connected with corresponding instruments on the surface vessel. I have also shown a ship compass 15 in this upper compartment to be used in determining the position of the diving apparatus for signaling desired shifting movements to the operators on the surface 100

130

vessel. In accordance with my said co-pending application I have shown the top of the diving cylinder provided with projecting fins 16 centrally located to assist in directing the apparatus when propelled horizontally; and also prevent its spinning; and I have shown a steering rudder 17 suitably connected to a steering post 18 which is in water-tight connection with the top 2 and inside the compartment 3 this post is provided with a tiller 19. There is a propeller 20 arranged outside of the cylinder upon a horizontal shaft 21 which latter extends through a stuffing box to the interior of the cylinder and it is connected with a motor 22 for driving the propeller. By means of the propelling device and steering device the diving cylinder may be propelled laterally and at the same time steered in order to move it to the desired location. The propeller may also be used to supplement the towing action of the surface vessel.

The means for securing the cylinder to the submerged vessel and for plumbing the cylinder comprises the following:

As has been stated above, there is an annular ring 8 of angle metal attached to the inner surface at the bottom end of the cylinder 1. Preferably there is attached to the exterior surface of the cylinder a pliable tubular member 23 which is adapted to fold like an accordion. This pliable member which in effect forms a continuation of the lower chamber 4, is prevented from collapsing and is caused to fold in regular order by means of inner and outer spiral springs. I have shown a spiral spring 24 the convolutions of which press outwardly against the inner surface of the accordion member 23 and this spring is shown as having one end connected at 25 with the annular ring 8 referred to above. There is another coiled spring 26 and it is so disposed that its convolutions lie intermediate the convolutions of the spring 24. This second spring 26, however, is disposed to engage the outer surface of the pliable accordion member 23 and it is suitably anchored by being attached to the outside of the lower end of the cylinder and to the ring 27. The effect of these inner and outer springs which are of relatively different and slightly varying diameters is to hold the pliable member 23 in cylindrical form with the pliable member 23 corrugated as shown in the drawings, and they permit this corrugated and pliable wall to be folded or collapsed either parallel with the bottom of the cylinder or to be collapsed on an angle with relation thereto, as shown in Figure 7, or to be curved at the bottom to conform to the contour of the vessel plate to which it is attached.

There is a metal ring 27 secured to a gasket 28, of annular shape and preferably made of rubber, and this same gasket is also attached to the bottom edge of the pliable member 23

by a water-tight connection. The annular ring 27 is provided with a number of socket members 29 arranged around the circle and having a ball and socket connection 30 with the threaded members 31 forming part of a plurality of turn buckles or sleeve nuts. The ring 8 which is attached to the cylinder is provided with corresponding socket members 32 which holds the heads 33 of the upper members 34 of the turn buckles, these members having threads which are reverse to the threads on the lower members 31. The nuts or sleeves 35 engage the upper and lower members 34, 31 of the turn buckles and when they are turned in one direction they act on the reverse threads to lengthen the turn buckles; whereas, when operated in an opposite direction they serve to shorten the turn buckles. These turn buckles may be operated by the crew while standing within the chamber 4 to make the gasket 28 and the ring 27 conform to the plate 70.

The upper portion of the diving cylinder, to wit, the top 2, is provided with an annular ring 36 the inner surface of which is of spherical shape to guide the spherical ball member 37 which is movable universally within the member 36, the connection between these two members being adapted to exclude the passage of water into the diving cylinder. The spherical or ball member 37, which is itself hollow, is provided with a number of apertures around the circle through which pass the supporting bolts 39 which are pivotally attached at 40 to the inner surface of the top member 2. Each of these supporting bolts 39 is provided with nuts and lock nuts 41 adapted to press upwardly on the flange 38 for the purpose of supporting the ball member 37 in close fitting contact with the socket member 36. These several bolts may be adjusted to incline the ball member 37 in various positions in relation to the diving cylinder. For instance, in Figure 7 the nuts on the bolts 39 at the left side of the ball member 37 are shown in a relatively lower position than those at the right of the ball member, whereas in Figure 11 the reverse of this condition is shown, so that the ball member 37 is tilted in the opposite direction in relation to the diving cylinder. The top of the ball member 37 is provided with a stuffing box containing the packing ring 42 which is adapted to be held in water-tight connection with the outer member 44 of the telescopic tube by means of the clamping nut 43. This connection permits the outermost member of the telescopic tube to slide with relation to the ball member 37 and to exclude water from entering between these members and reaching the interior of the cylinder.

The collapsible tube is composed of a plurality of tubular members adapted to telescope one within the other. The section

130

44 which is the outermost one of the group shown herein is provided with an enlarged or flared bottom portion 45 to the under side of which is permanently attached a gasket 46 preferably made of rubber, this gasket serving to form a seal between the lower portion of the tube member and the dividing wall 5 within the cylinder. I have shown a number of eyes 47 arranged around the flared portion 45 of the tube member 44 to which suitable lifting cables 48 may be secured, and these are attached to the tackles 49. Ropes or cables 50 engage over the sheaves of this tackle as well as the sheaves of the block 51 which are suitably supported on the brackets 52 within the cylinder, and by manipulating these latter ropes the entire telescoping tube may be lifted by sliding it upwardly within the ball member 37. These may also be used for plumbing the tube. When the flared end 45 of the outer tube member is lifted to the position shown in Figure 10, the bolts 53 which are pivoted to brackets 54 within the ball member are received through apertures 25 around the flared portion 45 and the wing nuts 55 are screwed onto these bolts to securely fasten the tube member in elevated position and at the correct inclination. The tube member 44 is shown provided with a bottom wall 56 suitably attached to the cylindrical wall, and this bottom wall forms a support for the nest of tube members which lie within the outer tube member. I have shown a number of tubular members 57 of 30 slightly different diameters, all of which are adapted to slide one within the other and within the outer tube member 44. These several tube members are similar to each other except in size. Each has an inwardly turned flange 58 at its upper end to serve as a guide for the next smaller tube with the exterior of which it engages. In addition, each section has an outwardly turned flange 59 at its bottom end. Adjacent the upper 35 end of each of these sections there is an inwardly projecting rib 60 of a thickness corresponding with the space between the walls of two adjacent tube sections. There is a gasket 61 on the outwardly turned flange 59 and this is adapted to form a water-tight connection between this flange and the inwardly projecting rib 60 of an adjacent tube section. These several tube sections also have, preferably, threaded apertures just above the 40 packing rings 61 into which are adapted to be screwed the bolts 62 for the purpose of resting on the rib 60 to hold the several tube sections one on the other when in extended condition. Any other means may be employed for supporting the sections one on the other. The innermost tube section 63 which is the smallest in diameter, is provided with the outwardly turned flange 59 at the bottom, but the inturned flange at the top is 45 omitted and instead there is an angle metal

ring 64 secured to the outer surface at the top of this tube and to this ring is secured a top wall 65 having a central opening which is adapted to be closed by a preferably downwardly swinging air-tight door to hold air pressure while the telescopic tube is being extended. Around the outer and projecting portion of the top 65 there are apertures to receive the rings 67 on the ends of the cables 68.

Operation

The diving apparatus may be carried on a vessel to the approximate location where the salvaging operations are to be carried on. The crew to accompany the device will enter the cylinder before it is lowered into the water and if desired one or more of the crew may be located in the compartment 3 which, during at least part of the operation, may be under atmospheric pressure, and one or more of the crew may be carried in the chamber 4 which will be under high pressure at least until the diving device is attached to the submerged vessel. Those remaining in the compartment 3 will have access to the telephone for communicating instructions to the surface vessel, and will also have control of the valves for admitting compressed air, as well as the propelling motor 22 and the steering tiller 19. When the device is ready to be lowered from the surface vessel by suitable tackle connected by means of the cables 69 the telescoping rescue tube will be in collapsed condition, as shown in Figure 3 with the flared end 45 of the outermost tube section resting on the deck or platform 5, and sealed by the gasket 46 so that air pressure cannot pass between the compartment 3 and the interior of the collapsible tube at this time. When the cylinder 1 is lowered into the water, the valve 11 will be manipulated to allow compressed air, which is preferably fed from a pump on the surface vessel, through the tubes 10, 12, to enter the lower compartment 4, until this pressure is sufficient to balance the external water pressure and prevent water from entering the open bottom of the cylinder. The compressed air in the compartment 4 will hold the hatch 6 closed, as well as the hatch 7, so that the compartments 3 and 4 are shut off from each other, and the compartment 3 may, therefore, remain at atmospheric pressure while the compartment 4 is at higher pressure necessary to exclude the water from this compartment. As the cylinder goes down to greater depths in the water, the valve 11 may be so manipulated as to increase the air pressure in the compartment 4 to correspond with the increased water pressure as the cylinder descends.

When the cylinder has been placed in its final position against the submerged vessel, the crew in the compartment 4 will adjust the several nuts 35 of the turn buckles, until the

ring 27 and gasket 28 assume an angle corresponding with the angle of the deck or hull plate 70 of the submerged vessel. This will permit the gasket 28 to come to rest on the deck or hull of the submerged vessel, as shown in Figure 7, while the cylinder 1 remains in a vertical position, or nearly so. For this purpose some of the nuts 35 may be turned in one direction while others are turned in another direction, in order to incline the ring 27 and gasket 28 in relation to the bottom of the cylinder 1. During this adjustment the pliable member 23 is permitted to expand or contract, similar to an accordion, but it will always be held in distended condition circumferentially by the internal coiled springs 24, 26. When the gasket 28 is evenly seated against the deck or hull plate 70 to form a water-tight or approximately water-tight connection, the crew may drill and tap holes partly through the plate 70 by means of drills and taps which may be operated by compressed air attached to the pipe 10. Bolts are then passed through apertures in the ring 27 and gasket 28 into these tapped holes in the plate 70 to secure the lower end of the accordion member to the submerged vessel in water-tight relation. The compressed air within the compartment 4 may be blown off to reduce this compartment to atmospheric pressure or pressure approximately that of the submerged vessel. The external water pressure will then supplement the holding of the gasket 28 tightly against the hull or deck plate 70. This blowing off may be done at a rate which will safely decompress the crew in compartment 4.

The diving apparatus having been applied to the sunken vessel, the telescopic tube may now be set into operation. For this purpose the ropes 50 will be manipulated for the purpose of raising the stack of tubes, and to plumb the tubes. The several nuts 41 may be adjusted to hold the ball member 37 in any position necessary to make the tube stand vertically even though the cylinder 1 is inclined, as shown in Figure 7. Of course, where the cylinder remains vertical, as in Figure 3, no adjustment of the ball member 37 is necessary. When the ropes 50 are operated, the stack of tubes is lifted, the outer tube 44 sliding in the stuffing box at the top of the ball member 37. It is necessary to lift the stack of tubes until the bolts 53 can be secured in the portion 45 of the outer tube, and if this cannot be done by the ropes 50 alone, compressed air may be admitted into the chamber 3 and this air will force the stack of tubes upwardly. The bolts 53 are then secured as described above. By means of the valve compressed air is admitted into the space within the tube between the upper door 66 and the lower door 71 from the compartment 3. The outwardly extending flange 59 and its gasket 61 of one tube section will come

into engagement with the rib 60 on the next adjacent tube section, whereupon bolts 62 will be inserted through the inner tube member to rest on the rib 60 of the next adjacent tube section. In this manner the several sections will rise, one within the other, until all the flanges 59 engage the ribs 60. In Figure 1 I have shown the tube fully extended, so that the upper section projects above the surface of the water.

The guy cables 68 attached to the upper end of the extended tube will have suitable anchors or weights on their opposite ends, which will be placed from the surface vessel at suitable points on the sea bottom around the tube and the cables 68 are attached to the upper end of the tube and are tightened so that together with the anchors they will serve to guy the tube and maintain it in proper vertical position against the action of water currents, wind and waves. If desired, a rope ladder will extend through the length of the telescoping tube to permit persons to climb from the diving cylinder 1 upwardly through the tube, and out of the top end of the latter. The pressure within the cylinder 1 may be blown off after the telescoping tube has been raised and the bolts 62 have been applied, so that the door 71 may be opened and the persons traveling to the top of the tube may open the door 66 and leave the upper end of the tube.

The pressure may be blown off in the chamber 4 and the hatch 7 may be opened to permit the crew in the compartment 3 to pass into the compartment 4 or vice versa. The crew, with suitable apparatus not shown, may now work in the chamber 4, and within the space provided by the accordion member drill, burn, cut or saw a suitable opening in the plate 70 in the space surrounded by the gasket 28 in order to give access to the interior of the submerged vessel. If the gasket 28 is located around the hatch of the submerged vessel, as shown in my co-pending case, it will only be necessary to open the hatch when the pressure in the compartment 4 has been blown off. Where the apparatus is not, however, located adjacent the hatch, then a hole may be made in the plate 70 in any manner, as above set forth. When this hole has been made in the plate 70, then, if the compartment of the submerged vessel where the opening is made is water-tight, the crew may pass through the opening into the submerged vessel for rescuing members of the vessel's crew or for salvage purposes, or to make repairs to the submerged vessel. If it is found, however, when the hole is first started through the plate 70 that the compartment in the submerged vessel is filled with water, compressed air may be immediately admitted into the compartment 4 of the diving apparatus to prevent water from forcing

from the submerged vessel into the bottom of the diving apparatus.

If members of the crew pass into the compartment 4 of the diving apparatus after the latter has been reduced to atmospheric pressure, they will not be subjected to high pressure during any part of the rescue work.

From now on, communication may be carried on from the submerged vessel through the diving cylinder 1 and through the telescoping tube, in atmospheric pressure, so that there is no necessity for subjecting the rescued persons to any decompression operation when they arrive at the surface of the water. For this reason the rescue operations may be carried on rapidly and without injury to the rescued persons. Furthermore, various salvaging operations may be conducted while the apparatus is in the condition just described.

When the operations upon the submerged vessel have been completed, it may be desirable to apply a patch or in some manner close the opening which was made in the plate 70 of the submerged vessel. When the salvaging operations have been completed, the diving apparatus may be restored to its original condition by reversing the operations.

While I have described one method of using the present apparatus, it will be apparent that the device may be manipulated in various other ways.

In Figure 2 I have shown weights 72 resting on the annular ring 8 within the compartment 4 and connected by flexible connections 73 with suitable supporting rings 74 and tackle 75 within the compartment 4 and these weights may be manipulated through the open bottom of the diving apparatus in the same manner that the weights are manipulated in my said co-pending application.

Having described my invention, what I claim is:

1. A diving apparatus comprising a chamber having an open bottom and adapted to contain compressed air, an accordion member attached to the open bottom of said chamber and having means for attachment to a deck or hull plate of a vessel whereby said chamber will form an enclosure for a portion of said plate, and means operable from within said chamber for adjusting the angle of the lower portion of said accordion member in relation to the angle of said chamber, comprising a series of turnbuckles connected between said chamber and the lower portion of said accordion member.

2. A diving apparatus including a chamber adapted to be submerged and to contain compressed air, a tube to form a means of passage between the submerged chamber and the water surface, said tube comprising sections adapted to telescope one into the other, the tube being adapted to telescope in said chamber, and means for supporting the lower end

of said tube in the upper portion of said chamber.

Signed at the city, county and State of New York, the 21st day of March, 1928.

JOHN F. O'ROURKE.
